UNITED STATES PATENT OFFICE

CHARLES MARKS AND CHARLES S. BRUDER, OF PHILADELPHIA, PENNSYLVANIA

WRITING GUIDING MACHINE

Application filed June 27, 1931. Serial No. 547,426.

This invention relates to an improved machine for causing the application of names to various articles, substantially regardless of their length, width and height, such as school bags, brief cases, pocket books, leather folders, dress suit cases, books, cameras and the like.

Previously names of the owners of such articles when purchased are ordered printed on the articles which takes time, and in some business houses a nominal charge is made, for applying the names of the owners to the articles purchased.

The present invention has for its purpose to facilitate the application of an owner's name to a school bag, brief case, camera or similar article in the owner's hand writing and in gold leaf. The fact is the purchaser of a school bag, brief case, book, pocket book or leather folder or camera, at the time the purchase is made may apply his or her own signature to the article, or write his or her name on a slip of paper, which can be clamped in position by the machine over the gold leaf, and the name traced or forced through upon the article, by means of an electric pencil.

Prior to the advent of the machine herein described, the gold leaf paper has been held flat by two strips or by the hand, while an electric pencil may be used to write the name, in which case the gold leaf transfers fast to the article.

In this method the gold leaf paper is very apt to slip or become wrinkled, in which case the name would not be accurately and evenly applied.

With the present type of machine it is the purpose to provide a base plate provided with an elongated opening under which the gold leaf paper passes, the opening having marginal flanges turned down to clamp the gold leaf paper in position, in order to hold the gold leaf smooth and even, so that the name can be applied accurately, by means of an electric pencil which operates through the opening.

Another purpose is to provide, in a machine of this kind, a base plate provided with snap fasteners, which may cooperate with similar fasteners on the exterior of a pencil

pouch or compartment on a school bag, for the purpose of holding the base plate in position, with the gold leaf paper positioned under the opening, to enable the name to be written with accuracy.

Still another purpose is to provide, in a machine of this kind supporting brackets for the roll of gold leaf, in conjunction with means on the base plate for drawing the gold leaf taut under the guide opening.

A further purpose is to provide in a machine of this character, clamping means for a brief case, dress suit case, book, pocket book or folder, a camera or any other article, so that the article may be held in position, with the base plate hingedly supported on one of the clamps, making it possible to tilt the base plate to enable the operator to inspect the name at intervals during its application, in which case the base plate will fold back into position in register with the name being applied.

A still further purpose is to provide a base board carrying the clamps, the board being supplied with scored lines horizontally and vertically, so as to act as guides in placing the brief case or other article in position, so that the name can be applied in a substantially horizontal position.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawings and claimed.

In the drawings:—

Figure 1 is a view in perspective of the improved writing guiding machine, illustrating the same constructed in accordance with the invention, showing a brief case in position, in order that the name may be applied in gold leaf by means of an electric pencil, the latter being indicated in position, in the act of applying the name.

Figure 2 is a view in elevation showing a book clamped in position.

Figure 3 is a view similar to Figure 2 but showing a camera in position between the 5 clamps.

Figure 4 is a sectional view on line 4—4 of Figure 1 transversely through the machine, showing the construction of the base plate, the clamps, and the manner in which the gold 10 leaf is held in position and drawn taut, and illustrating the base plate tilted upwardly in dotted lines and to an angle, so as to inspect the writing.

Figure 5 is a perspective view of the base 15 plate with the brackets applied to a school bag, snap fasteners of the school bag and the base plate cooperating to hold the plate in position.

Figure 6 is a sectional view on line 6—6 of 20 Figure 5.

Figure 7 is a longitudinal sectional view on line 7—7 of Figure 6 showing the snap fasteners, and illustrating the ends of the brackets in section, to illustrate the supporting 25 of the roll of gold leaf.

Figure 8 is a detail view showing the portion of the base plate with one of the clamps for holding the gold leaf in place.

Figure 9 is a sectional view on line 9—9 of 30 Figure 7.

Figure 10 is a bottom plan view of the base plate.

Figure 11 is a sectional view on line 11—11 of Figure 2.

Figure 12 is a sectional view on line 12—12 of Figure 1.

Referring to the drawings 1 identifies a base board, the upper surface of which is provided with horizontal intersecting scored 40 lines 2 and 3 which are used as guides to align a brief case, book or the like in position, when applying a name on an article, to make sure that the article is held straight and even so that the name can be applied 45 with accuracy.

The board has a transverse recess or groove 4, in which a clamping bar 5 is secured. It is obvious that the board may be of any dimensions, while the clamp can be of any 50 length.

A second clamping bar of similar length and width 5a is provided, and its opposite ends have bifurcations 6 causing forks 7 to be formed. The bifurcations 6 straddle 55 grooves 8 formed in collars 9, which are slidably mounted upon guide rods 10, which rise from and are fixed to the ends of the clamping bar 5. The guide rods 10 have flat faces 11 against which the extremities of the 60 thumb screws 12 bite for holding the collars in different positions on the rods. It is obvious that the collars can be raised and lowered, so that the upper clamping bar 5a can be supported in different positions, for accommodating articles of various dimensions.

Intermediate the ends of the clamping bar 5a and in suitable spaced relation are feet 13, which are secured to the clamping bar 5a by means of screws 14. These feet are thick enough to hold the bar 5a raised in the center and spaced from a brief case, folder or school bag or similar article when in position, it being possible to bend the bifurcated ends of the clamping bar 5a downwardly, so as to insure pressure on the feet, to clamp the brief case or school bag in position. The central part of the clamping bar 5a has a cut away portion or recess 15, to accommodate a portion of the lock on the brief case.

The writing guiding machine includes a 80 base plate 16, from which the brackets 17 rise, the brackets being secured in position by means of screws 18. The screws 18 secure to the brackets certain leaves of hinges 19 to the feet of the brackets, the other leaves 85 of the hinges being secured by screws 20 to the clamping bar 5a. In this manner the base plate 16 is hingedly supported on the clamping bar 5a so that it can be tilted upwardly and rearwardly for the purpose of 90 inspecting the writing being applied to the brief case or other article.

The brackets 17 are provided for the purpose of supporting a roll of gold leaf, identified at 20a. The gold leaf is rolled on a 95 spindle 21, the ends of which have depressions 22 for the reception of the pintles 23 of the screws 24, which are threaded in bearings at the upper ends of the brackets. It is possible to tighten the screws 24 to hold the 100 spindle in position and prevent the gold leaf from unwinding. Suitable thumb nuts 25 are threaded on the screws for tightening against the brackets to hold the screws from loosening.

The base plate 16 is provided with an elongated rectangular opening 26, the longitudinal edge portions of which have flanges 27 to engage with the gold leaf, thereby holding the gold leaf in position under the opening 105 26. Adjacent the longitudinal portions of the opening 26 scored lines 28 are provided, which are designed for centralizing the writing of the name on the brief case or other article. For example, in writing the name 110 John H. Doe through the opening by means of an electric pencil for transferring the gold leaf to the brief case or other article, the electric pencil would be placed in a position, in order to apply the name, so that the scored lines 28 would approximate the center of the name John H. Doe. In other words the scored lines 28 would approximate a position just a trifle to the left of the middle initial "H", in which case, the name may be centralized on the brief case or other article. Adjacent the opposite ends of the opening 26, a trifle to one side the longitudinal center of the opening, scored lines 29 are formed on the surface of the base plate. These lines 115 29

facilitate the arranging of the letters of the name substantially even with the lines, when the name is written by means of the electric pencil.

5 The base plate 16 has longitudinal slots 30 and 31, through which the gold leaf paper passes. The gold leaf passes through the opening 30 under the base plate under the elongated opening 26, and then through the slot 31. Suitable clamping clips 32 are pivoted at 33 to the base plate 16, and which are in the form of leaf springs. These clamping clips are so positioned that the nubs 35 carried by the free ends of the clips may engage 10 with the gold leaf, when the clips are positioned as in Figure 1 of the drawings. When the clips are disposed as in Figure 1, the nubbed ends of the clips overlie the gold leaf, thereby holding the gold leaf in position 15 while writing the name and transferring it on to the brief case or other article. In the act of moving the clips in order to overlie the gold leaf prior to passing through the slot 30 and subsequently to leaving the slot 31, the 20 frictional action of the nubs of the clips act to draw the gold leaf taut, in a position under the elongated opening 26 in the base plate.

The base plate 16 is provided with downwardly extending male snap fasteners 37, 25 which may enter female fasteners 38, which may be carried by a pencil pouch or pocket 39 of a school bag, for the purpose of holding the base plate 16 in position, while transferring an individual's name to the school 30 bag. When using the base plate 16 for this purpose, it is possible to use it with or without the brackets. By using a base plate without the brackets the roll of gold leaf is very apt to come unwound, while with the brackets it is possible to facilitate the transferring 35 of a name, for the reason that the roll of gold leaf is prevented from unwinding. For example when the brackets are used, the clips to the front of the base plate may be disposed 40 to overlie the gold leaf where it leaves the slot 31. At the time of moving the clips, the roll of gold leaf may be held tight, by tightening up on the screws, then afterwards the clips to the rear of the opening 26 may be 45 moved to overlie the gold leaf, and in this case the gold leaf under the opening 26 is drawn taut.

The invention having been set forth, what is claimed is:

55 1. In a writing guiding machine, a base plate having an elongated central opening under which gold leaf passes, means for retaining the base plate in fixed relation to the article to which a name is to be transferred by operating a heated tool upon the gold leaf at a point through the opening, said base plate having slots on opposite longitudinal sides of the opening through which the gold leaf passes to pass under the opening and be drawn taut.

2. In a writing guiding machine, a base plate having an elongated central opening under which gold leaf passes, means for retaining the base plate in fixed relation to the article to which a name is to be transferred by operating a heated tool upon the gold leaf at a point through the opening, said base plate having slots on opposite longitudinal sides of the opening through which the gold leaf passes to pass under the opening and be drawn taut, and means mounted upon the base plate and adapted to overlie the gold leaf to hold it drawn taut.

70 3. In a writing guiding machine, a base plate having an elongated central opening under which gold leaf passes, means for retaining the base plate in fixed relation to the article to which a name is to be transferred by operating a heated tool upon the gold leaf at a point through the opening, said base plate having slots on opposite longitudinal sides of the opening through which the gold leaf passes to pass under the opening and be drawn taut, the longitudinal edges of the openings having downward flanges to bear against the gold leaf and hold it flat against the article to which the name is being transferred.

75 4. In a writing guiding machine, a base plate having an elongated central opening under which gold leaf passes, means for retaining the base plate in fixed relation to the article to which a name is to be transferred by operating a heated tool upon the gold leaf at a point through the opening, said base plate having slots on opposite longitudinal sides of the opening through which the gold leaf passes to pass under the opening and be drawn taut, the longitudinal edges of the openings having downward flanges to bear against the gold leaf and hold it flat against the article to which the name is being transferred, and means mounted upon the base plate and adapted to overlie the gold leaf to hold it drawn taut.

80 5. In a writing guiding machine, a base plate provided with an elongated central opening below which a sheet of gold leaf from a roll passes, said base plate having slots adjacent opposite longitudinal sides of the opening through which the gold leaf passes, means mounted on the base plate to overlie and frictionally contact with the gold leaf at points beyond the slots to hold the gold leaf taut below the opening, and brackets provided with means for cooperating with a spindle of the roll of gold leaf, to prevent unwinding of the roll.

85 6. In a writing guiding machine, the combination with a base plate provided with a central longitudinal opening, below which a sheet of gold leaf from a roll passes, of brackets rising from the base plate and provided with means at their ends for engagement with a spindle of the roll of gold leaf to prevent 90 95 100 105 110 115 120 125 130

the roll from unwinding, said base plate having slots adjacent opposite sides of the opening through which the gold leaf passes to appear below the opening, spring clips carried by the base plate and adapted to overlie the gold leaf at points beyond the slots to hold the gold leaf taut.

7. In a writing guiding machine, a base plate provided with an elongated central opening below which a sheet of gold leaf from a roll passes, said base plate having slots from a roll passes, said base plate having slots adjacent opposite longitudinal sides of the opening through which the gold leaf passes, means mounted on the base plate to overlie and frictionally contact with the gold leaf at points beyond the slots to hold the gold leaf taut below the opening, and brackets provided with means for cooperating with a spindle of the roll of gold leaf, to prevent unwinding of the roll, the longitudinal edges of the opening having flanges to bear against the gold leaf to hold same flat against the article to which a name may be transferred.

8. In a writing guiding machine, the combination with a base plate provided with a central longitudinal opening, below which a sheet of gold leaf from a roll passes, of brackets rising from the base plate and provided with means at their ends for engagement with a spindle of the roll of gold leaf to prevent the roll from unwinding, said base plate having slots adjacent opposite sides of the opening through which the gold leaf passes to appear below the opening, spring clips carried by the base plate and adapted to overlie the gold leaf at points beyond the slots to hold the gold leaf taut, the longitudinal edges of the opening having flanges to bear against the gold leaf to hold same flat against the article to which a name may be transferred.

9. In a writing guiding machine, a base plate provided with an elongated central opening below which a sheet of gold leaf from a roll passes, said base plate having slots adjacent opposite longitudinal sides of the opening through which the gold leaf passes, means mounted on the base plate to overlie and frictionally contact with the gold leaf at points beyond the slots to hold the gold leaf taut below the opening, and brackets provided with means for cooperating with a spindle of the roll of gold leaf, to prevent unwinding of the roll, a pair of clamping bars, between which an article to which the name may be transferred may be clamped, means for hingedly mounting the base plate on one of the clamping bars whereby the base plate may be tilted upwardly and backwardly for inspecting the name being transferred to the article.

10. In a writing guiding machine, the combination with a base plate provided with a central longitudinal opening, below which a

sheet of gold leaf from a roll passes, of brackets rising from the base plate and provided with means at their ends for engagement with a spindle of the roll of gold leaf to prevent the roll from unwinding, said base plate having slots adjacent opposite sides of the opening through which the gold leaf passes to appear below the opening, spring clips carried by the base plate and adapted to overlie the gold leaf at points beyond the slots to hold the gold leaf taut, a pair of clamping bars, between which an article to which the name may be transferred may be clamped, means for hingedly mounting the base plate on one of the clamping bars whereby the base plate may be tilted upwardly and backwardly for inspecting the name being transferred to the article.

11. In a writing guiding machine, the combination with a base plate provided with a central longitudinal opening, below which a sheet of gold leaf from a roll passes, of brackets rising from the base plate and provided with means at their ends for engagement with a spindle of the roll of gold leaf to prevent the roll from unwinding, said base plate having slots adjacent opposite sides of the opening through which the gold leaf passes to appear below the opening, spring clips carried by the base plate and adapted to overlie the gold leaf at points beyond the slots to hold the gold leaf taut, upper and lower clamping bars, between which an article may be clamped, whereby a name may be transferred thereto at a point through the opening, and means operatively associated with the opposite ends of the clamping bars for permitting the upper clamping bar to be arranged in different adjusted positions.

12. In a writing guiding machine, the combination with a base plate provided with a central longitudinal opening, below which a sheet of gold leaf from a roll passes, of brackets rising from the base plate and provided with means at their ends for engagement with a spindle of the roll of gold leaf to prevent the roll from unwinding, said base plate having slots adjacent opposite sides of the opening through which the gold leaf passes to appear below the opening, spring clips carried by the base plate and adapted to overlie the gold leaf at points beyond the slots to hold the gold leaf taut, upper and lower clamping bars, between which an article may be clamped, whereby a name may be transferred thereto at a point through the opening, and means operatively associated with the opposite ends of the clamping bars for permitting the upper clamping bar to be arranged in different adjusted positions, said last mentioned means comprising guide rods on the lower clamping bars, collars on the rods and provided with diametrically opposite grooves, the upper clamping bars having bifurcations to engage the grooves and strad-

dle the collars, and means for holding the collars in different adjusted positions on the rods, whereby articles of different height may be clamped in position.

- 5 13. In a writing guiding machine, the combination with a base plate provided with a central longitudinal opening, below which a sheet of gold leaf from a roll passes, of brackets rising from the base plate and provided with means at their ends for engagement with a spindle of the roll of gold leaf to prevent the roll from unwinding, said base plate having slots adjacent opposite sides of the opening through which the gold leaf passes to appear below the opening, spring clips carried by the base plate and adapted to overlie the gold leaf at points beyond the slots to hold the gold leaf taut, upper and lower clamping bars, between which an article may be clamped, whereby a name may be transferred thereto at a point through the opening, and means operatively associated with the opposite ends of the clamping bars for permitting the upper clamping bar to be arranged in different adjusted positions, and a base board on which the lower clamping bar is mounted, the upper surface of the base board having scored lines for facilitating the position of the article whereby the name transferred thereto may be applied with accuracy.
14. In a writing guiding machine, the combination with a base plate provided with a central longitudinal opening, below which a sheet of gold leaf from a roll passes, of brackets rising from the base plate and provided with means at their ends for engagement with a spindle of the roll of gold leaf to prevent the roll from unwinding, said base plate having slots adjacent opposite sides of the opening through which the gold leaf passes to appear below the opening, spring clips carried by the base plate and adapted to overlie the gold leaf at points beyond the slots to hold the gold leaf taut, upper and lower clamping bars, between which an article may be clamped, whereby a name may be transferred thereto at a point through the opening, and means operatively associated with the opposite ends of the clamping bars for permitting the upper clamping bar to be arranged in different adjusted positions, said last mentioned means comprising guide rods on the lower clamping bars, collars on the rods and provided with diametrically opposite grooves, the upper clamping bars having bifurcations to engage the grooves and straddle the collars, and means for holding the collars in different adjusted positions on the rods, whereby articles of different height may be clamped in position, and a base board on which the lower clamping bar is mounted, the upper surface of the base board having scored lines for facilitating the positions of

the article whereby the name transferred thereto may be applied with accuracy.

15. In a writing guiding machine, a base plate having an elongated opening under which gold leaf passes, means for retaining the base plate in fixed relation to an article to which a name is to be transferred by operating a heated tool upon the gold leaf at a point through the opening.

16. In a writing guiding machine, a base plate having an elongated opening under which gold leaf passes, means for retaining the base plate in fixed relation to an article to which a name is to be transferred by operating a heated tool upon the gold leaf at a point through the opening, said base plate having means on opposite longitudinal sides of the opening to permit the passage of the gold leaf to pass under the opening and be drawn taut.

17. In a writing guiding machine, a base plate having an elongated opening under which gold leaf passes, means for retaining the base plate in fixed relation to an article to which a name is to be transferred by operating a heated tool upon the gold leaf at a point through the opening, said base plate having means on opposite longitudinal sides of the opening to permit the passage of the gold leaf to pass under the opening and be drawn taut, and means adjacent the last named means and adapted to engage the gold leaf at points where it passes through the plate to hold the gold leaf taut under the opening.

18. In a writing guiding machine, a base plate having an elongated opening under which gold leaf passes, means for retaining the base plate in fixed relation to an article to which a name is to be transferred by operating a heated tool upon the gold leaf at a point through the opening, said base plate having means on opposite longitudinal sides of the opening to permit the passage of the gold leaf to pass under the opening and be drawn taut, and means adjacent the last named means and adapted to engage the gold leaf at points where it passes through the plate to hold the gold leaf taut under the opening, the longitudinal edges of the opening having downward flanges to bear against the gold leaf and hold it flat against the article to which the name is being transferred.

In testimony whereof we affix our signatures.

CHARLES MARKS.
CHARLES S. BRUDER.
